UNITED STATES PATENT OFFICE.

GEORGE E. WARREN, OF SWAMPSMOTT, MASSACHUSETTS, ASSIGNOR TO UNITED SHOE MACHINERY COMPANY, OF PATERSON, NEW JERSEY, A CORPORATION OF NEW JERSEY.

STEAM-GENERATOR.

1,152,579.

Specification of Letters Patent.

Patented Sept. 7, 1915.

Application filed December 1, 1913. Serial No. 803,956.

To all whom it may concern:

Be it known that I, GEORGE E. WARREN, a citizen of the United States, residing at Swampscott, in the county of Essex and State of Massachusetts, have invented certain new and useful Improvements in Steam-Generators; and I do hereby declare the following to be a full, clear, and exact description of the invention, such as will enable others skilled in the art to which it appertains to make and use the same.

This invention relates to steam generators.

The primary object of the invention is to produce a steam generator in which kerosene or other analogous liquid hydro carbon fuel may be used and which will operate in a reliable manner to maintain a substantially constant pressure of steam in the boiler.

With this object in view, the invention consists of certain novel and improved constructions and combinations set forth in the following description and pointed out in the claims, the advantages of which will be obvious to one skilled in the art.

In the drawings illustrating a steam generator embodying the invention in its preferred form, Figure 1 is a view in front elevation of the generator and Fig. 2 is a view in sectional elevation of the generator taken substantially in the central plane thereof.

The steam generator illustrated in the drawings comprises a cylindrical hollow supporting stand indicated at 2, upon which is mounted a boiler 4 surrounded by a sheet metal casing 6. The steam from the boiler is conducted to any desired point by means of an outlet pipe 8 secured to its end in the top of the boiler and the steam or water to which it may have condensed in circulating through the system is returned to the boiler by a return pipe 10 connected with the boiler by a horizontal pipe 12.

14 indicates a pipe connected with the top of the boiler upon the upper end of which is mounted a safety valve 16 and to which is connected an exhaust nozzle 18, the flow of air or steam through the nozzle being controlled by a valve operated by a

hand wheel 20. A pipe 22 is connected with the pipe 12 and is provided with a funnel 24 through which water is introduced into the boiler, the funnel being covered by a strainer 26. The pipe 22 is opened and closed by a valve operated by a hand wheel 28.

The burner by which the boiler is heated is of the so-called wickless or blue flame type constructed for the use of kerosene or any analogous liquid hydro carbon fuel. Liquid fuels of this class have the advantage that they are not liable to explode or take fire even when handled carelessly and when used in a burner of the above type produce a very hot and substantially smokeless flame. This burner is located within the cylindrical supporting frame 2 beneath the boiler and comprises an annular fuel holder or trough 30 preferably constructed of sheet metal and made deeper at one side than at the other, as shown in Fig. 2. This trough is connected at its deeper side by means of a coupling 32, a flexible pipe 34, a second coupling 36 and a short pipe 38 with a liquid fuel reservoir 40 from which the liquid fuel is supplied to the burner. The reservoir 40 is supported upon brackets 42 secured to the side of the cylindrical supporting frame 2.

It will be obvious that when the liquid fuel is introduced into the reservoir 40 the level of the fuel in the fuel holder or trough 30 of the burner will be substantially the same as the level of the fuel in the reservoir. As is common in liquid fuel stoves employing wickless burners, the fuel in the reservoir is maintained at a constant level. In order to maintain this constant level of the liquid fuel in the reservoir, a tank 44 is supported above the reservoir 40 and is provided with a downwardly extending cylindrical nozzle 45 which projects through a circular opening in the upper wall or cover of the reservoir. The tank 44 is filled or partially filled with liquid fuel and is inverted and placed on the reservoir 40 as shown in Fig. 2 with its nozzle 45 extending down through the opening in the cover of the reservoir. The liquid flows through the nozzle of the tank into the reservoir until 100

the level of the liquid in the reservoir rises sufficiently to cover the opening in the nozzle. The tank 44 is provided with a valve 48 operated by a spring 50 to close the opening in the nozzle 45 when the tank is inverted preparatory to placing it in operating position with relation to the reservoir, and prevent the liquid from flowing out of the nozzle until the tank is placed in position. When the tank is placed in proper position on the reservoir, the valve is held open by contact of the valve stem 52 with the bottom of the reservoir. The pipe 38 is provided with a valve operated by a thumb piece 54 by which the operator may cut off the flow of liquid from the reservoir to the burner.

The burner is provided with a chimney which comprises inner and outer hollow perforated cylindrical sections 56 and 58 seated upon flanges on the trough 30 and an unperforated tapered section 60 secured at its upper end to the section 56 and closed at its lower end by means of a plate 62, which is held in place by means of a rod 64 secured at its lower end to the plate 60 and at its upper end to a member 66 located at the upper end of the section 56.

In burners of the type above described the size of the flame may be varied by varying the depth of the fuel in the burner. The level of the liquid in the burner is always the same as the level of the liquid in the reservoir 38, which is maintained constant in the manner above described. In order to vary the depth of the liquid in the burner, and thereby vary the size of the flame and the heat transmitted to the boiler, the burner is arranged for vertical movement with relation to the reservoir. In the construction illustrated, the fuel trough is seated upon a supporting ring 68 formed upon the end of an arm of a lever 70 pivoted on a pin 72 carried by the bracket 74, and the fuel trough is raised and lowered by swinging the lever.

It is desirable in steam generators to maintain the steam in the boiler at a substantially constant pressure and in the present embodiment of the invention mechanism controlled by the pressure of steam in the boiler is provided which acts automatically to raise and lower the fuel holder of the burner to vary the depth of fuel in the fuel holder and thereby vary the size of the flame as the pressure of the steam in the boiler falls below or rises above a predetermined point. This mechanism comprises a rod 78 passing through a sleeve 80 threaded into the bracket 74 and pivotally connected by means of a pin 76 with the other arm of the lever 70. The upper end of the rod 78 carries a cap 82 which engages the lower side of a diaphragm 84 clamped by

means of screws 86 between annular flanges 88 and 90 formed respectively on the bracket 74 and a pipe 92 connected with the pipe 12. The cap 82 at the upper end of the rod 78 is held in contact with the lower side of the diaphragm by means of a coiled spring 94 surrounding the rod and engaging at its extremities the cap 82 and a flange on the sleeve 80 respectively. The tension of this spring may be regulated by adjusting the sleeve 80. The diaphragm 84 forms a closure for a chamber 96 which opens into the pipe 12 and is connected by said pipe with the interior of the boiler. A pressure gage 97 connected with the pipe 12 is provided to indicate the pressure of the steam in the boiler.

In starting the generator, the operator first fills or partially fills the tank 44 and inverts the tank and places it in operating position, as shown in Fig. 2, on the reservoir 38. The liquid fuel will then flow into the reservoir 40 until the height of the liquid in the reservoir is sufficient to cover the opening in the nozzle 46. The valve operated by the thumb piece 54 is then opened to allow the liquid to flow through the series of pipes connecting the reservoir with the burner into the burner trough. Before the burner is lighted, since there is no pressure of steam against the upper surface of the diaphragm 84, the burner assumes its lowermost position. In order to regulate the depth of the liquid fuel in the trough so that it is at proper depth for starting the burner, the reservoir 40 is adjusted vertically to the desired height. To provide for this adjustment, the brackets 42 are provided with slots 98 and are secured to the cylindrical supporting frame 2 by means of screws 100 passing through the slots in the brackets 42 and screwed to the frame 2. When the burner has been lighted and the steam generated in the boiler exceeds a predetermined pressure, the diaphragm 84 is depressed by the pressure of the steam in the boiler and actuates the rod 78 and the lever 70 to raise the burner and thereby lower the level of the fuel in the trough of the burner. This will result in a reduction of the size of the flame with the consequent diminution of the amount of heat transmitted to the boiler. When the pressure of the steam in the boiler falls below this predetermined point, the reduction in the pressure upon the upper face of the diaphragm 84 allows the rod 78 to rise under the action of the spring 94 and the arm of the lever 70, which supports the burner, to fall and lower the burner. The depth of the liquid fuel in the trough 28 then increases and the size of the flame is increased so as to increase the heat transmitted to the boiler and the production of steam in the boiler.

The predetermined pressure at which the steam in the boiler is maintained may be varied by adjusting the sleeve 80 in the bracket 74 so as to increase or diminish the tension of the spring. With any given adjustment of the tension of the spring, the generator will operate to maintain the steam in the boiler at a substantially constant pressure determined by the tension of the spring 10 without attention on the part of the operator.

Having explained the nature and objects of the invention, and having specifically described a device embodying the same in its preferred form, what is claimed is:—

15 1. A steam generator, having in combination, a boiler, a burner comprising a vertically movable liquid fuel holder for heating the boiler, a liquid fuel reservoir connected with the fuel holder, means for maintaining a substantially constant level of liquid in the reservoir, and means controlled by the pressure of the steam in the steam chamber for raising and lowering the burner 20 to vary the depth of fuel in the burner and 25 thereby vary the size of the flame.

2. A steam generator, having in combination, a boiler, a burner comprising a liquid fuel holder for heating the boiler, a liquid fuel reservoir connected with the fuel holder, means for maintaining the liquid fuel in the reservoir at a substantially constant level, and means controlled by the pressure of the steam in the boiler for relatively moving the fuel holder and reservoir 30 to vary the depth of the fuel in the fuel holder and thereby vary the size of the flame.

3. A steam generator, having in combination, a boiler, a burner comprising a liquid fuel holder for heating the boiler, a liquid fuel reservoir connected with the fuel holder and means controlled by the pressure of steam in the boiler for relatively moving the fuel holder and reservoir to vary the depth of the fuel in the fuel holder and 40 thereby vary the size of the flame.

4. A steam generator, having in combination, a boiler, a burner comprising a liquid fuel holder for heating the boiler, a liquid fuel reservoir connected with the burner 50 and means acting automatically to move relatively the fuel holder and reservoir to vary the depth of liquid in the fuel holder and thereby vary the size of the flame in accordance with variations in the pressure of the 55 steam in the boiler.

5. A steam generator, having in combination, a boiler, a burner comprising a vertically movable fuel holder for heating the boiler, a pivoted lever supporting the fuel 30 holder, a liquid fuel reservoir connected with the fuel holder, means for maintaining the fuel in the reservoir at a substantially constant level and means controlled by the pressure of steam in the chamber for actuating

the lever to raise and lower the fuel holder 65 to vary the depth of fuel therein and thereby vary the size of the flame.

6. A steam generator, having in combination, a boiler, a liquid fuel burner comprising a fuel holder for heating the boiler, a liquid fuel reservoir connected with the fuel holder, a chamber connected with the boiler, a diaphragm closing the chamber and means operatively connected with the diaphragm for relatively moving the fuel holder and 70 reservoir to vary the depth of fuel in the fuel holder and thereby vary the size of the flame in accordance with variations in the pressure of steam in the boiler.

7. A steam generator, having in combination, a boiler, a liquid fuel burner comprising a vertically movable fuel holder for heating the boiler, a liquid fuel reservoir connected with the fuel holder, a chamber connected with the boiler, a diaphragm closing the chamber, and operative connections 85 between the burner and the diaphragm for moving the burner vertically from the diaphragm to vary the depth of the fuel in the fuel holder and thereby vary the size of the 90 flame in accordance with variations in the pressure of steam in the boiler.

8. A steam generator, having in combination, a boiler, a burner comprising a liquid fuel holder for heating the boiler, a liquid fuel reservoir connected with the fuel holder, a pivoted lever supporting the fuel holder, a chamber connected with the boiler, a diaphragm closing the chamber, and connections 95 between the diaphragm and the lever 100 for operating the lever from the diaphragm to raise and lower the fuel holder and to vary the depth of liquid in the fuel holder and thereby vary the size of the flame in accordance with variations in the pressure of 105 the steam in the boiler.

9. A steam generator, having in combination, a boiler, a burner comprising a liquid fuel holder for heating the boiler, a liquid fuel reservoir connected with the fuel holder, 110 means acting automatically to move relatively the fuel holder and reservoir to increase or decrease the depth of fuel in the fuel holder and thereby increase or decrease the size of the flame as the pressure of 115 steam in the boiler falls below or rises above a predetermined point, and provision for adjustment to vary this predetermined pressure.

10. A steam generator, having in combination, a boiler, a burner comprising a liquid fuel holder for heating the boiler, a liquid fuel reservoir connected with the fuel holder, a chamber connected with the boiler, a diaphragm closing the chamber, means operatively connected with the diaphragm for relatively moving the fuel holder and reservoir to increase or decrease the depth of fuel 125

in the fuel holder and thereby increase or decrease the size of the flame as the pressure of the steam falls below or rises above a predetermined point comprising a spring acting 5 on the diaphragm in opposition to the pressure of the steam in the boiler and provision

for adjusting the tension of the spring to vary the predetermined pressure.
